11 Claims. (Cl. 264—3)

1

The present invention relates to governors and, more particularly, to an improved variable speed centrifugal governor for internal combustion engines and the like.

It is well understood in the spring governor art that when using springs in which the deflection is proportional to the load, to resist the centrifugal forces in a governor, there can be only a narrow range of speed adjustment at which the governor can control the speed accurately. Various methods have been employed to compensate for the discrepancy between the rates of increase of the spring forces and the centrifugal forces at engine speeds other than that for which the springs are designed, but springs of non-proportional deflection rates are very difficult to produce accurately; and the method in which the effective moments of the spring forces are varied in their capacity to resist the centrifugal forces after translation of the latter to rotational force about an axis, are productive of heavy bearing loads and consequent friction.

Accordingly, a primary object is to provide a simple, compact, efficient and economical centrifugal governor for internal combustion engines, said governor being provided with a spring assembly or means for accurately controlling the speed of the engine over a wide range of adjustments, and which imposes a minimum of frictional load on the working parts of the governor, thus insuring a high degree of sensitivity and stability of performance under varying operating conditions and loads.

A further object consists in providing a spring assembly or system associated with the engine governor in such a manner that the spring forces are divided or distributed to facilitate control of the engine speed below the governed speed, either manually or by automatic means for idling the engine at low speed when power demands are intermittent.

A still further object consists in providing a centrifugal governor having a rotatable governor shaft and a spring assembly associated therewith for resisting the thrust resultant of the centrifugal forces at various speeds, and which consists of at least a pair of inclined or angularly disposed springs so mounted that the axes of the springs assume decreasing angles, with respect to the axis of the governor shaft, as the governor is adjusted for higher speeds.

A further object consists in providing a spring assembly for resisting the centrifugal force of the governor at various speeds, including a pair of

segmental or curved yoke members for adjustably mounting the ends of two pairs of springs to the intermediate portions of said segmental members, and in which the springs are moved substantially parallel with the axis of the governor shaft so as to exert a retractive force on a thrust member or collar slidable on the governor shaft, and in which the axes of the springs are at substantially equal angles to a plane through the governor shaft axis and the median line of the segmental members. The intermediate portions of said segmental members are pivotally connected to depending levers or other suitable means for changing the tension of the springs so that slight variations in the lengths and longitudinal displacement of the springs, or slight departure of the pivot connections of the segmental members with the levers from the plane of the governor shaft axis and the median line of the segmental members or yokes, may be compensated.

Another object consists in associating with the centrifugal governor and the spring assembly, an auxiliary spring for normally holding an operating lever against a thrust collar axially slidable on the governor shaft, and with a force which is proportionally less with respect to the force exerted by the main spring system, at the no-load position of the thrust collar, than the force exerted by the auxiliary spring in relation to the force exerted by the spring assembly at the full-load position of the thrust collar.

Other objects and advantages of the invention will become apparent from the following description when taken in conjunction with the accompanying claims and drawings.

Referring to the drawings wherein, for the purpose of illustration, are shown several preferred embodiments of the invention:

Figure 15 shows an engine performance chart.

Referring to the drawings, 15 designates the housing of the variable speed centrifugal governor which may be closed at one end by a removable cap 16 secured by the threaded bolts 17 (Fig. 1) to the forward or front end of the housing. The rear end 18 of the housing is formed with a central opening 19 which is in horizontal alignment with a similarly formed opening 20 in the cap 16 (Fig. 2). Extending into the housing 15 so as to be revolubly mounted therein is the governor shaft 21 which has its rear end journalled in a bearing 22 positioned in the opening 19. An annular ball bearing 23 is mounted in the wall of the opening 20 of the cap 16 so as to rotatably receive the shaft 21 which extends outwardly as at 24 from the end of the cap 16 so as to be operatively connected in any suitable manner, not shown, to the crank or drive shaft of an associated engine or the like, so as to rotate at a speed generally equal to or in excess of the speed of the engine shaft. Keyed or non-rotatably connected to the governor shaft 21 is a boss 25 having rearwardly curved diametrically disposed arms 26 (Fig. 2), to each of which is pivotally connected a fly-weight 27 by the pins 28 and the needle-type anti-friction bearings 29. A spacer sleeve 30 abuts at one end the boss 25 and has its opposite end reduced as at 31 so as to extend through the ball bearing 23 and be rotatably mounted therein. The opening 20 is provided with an oil-seal 32 to prevent escape of oil through the shaft opening during the operation of the governor. A thrust sleeve 33 is axially slidble on the governor shaft 21 and is provided at one end with an annular flange or collar 34 (Fig. 10) and its opposite end with an annular flange 35. The flanges 34 and 35 on the sleeve 33 are spaced from each other a sufficient distance to receive between them the opposed swinging members 36 of the fly-weights 27 (Fig. 2). Each of the fly-weights 27 has extending inwardly and radially toward the governor shaft 21, an arm 37 (Fig. 2) having a head 38 arranged to engage the outer face of the flange 34 of the sleeve 33. The arms 37 are positioned on opposite sides of the shaft 21 so that when the speed of the shaft 21 is such as to cause the fly-weights 27 to swing outwardly, this movement will simultaneously cause the arms 37 to press against the flange 34 and move the sleeve 33 axially and rearwardly of the shaft 21. The flange 35 on the sleeve 33 is spaced from the adjacent end thereof so as to provide a bearing portion 39 (Fig. 10) on which is mounted a conventional thrust collar indicated generally as at 40 and which may comprise end discs 41 and 42 and an intermediate ball bearing disc 43 arranged to engage complementary annular raceways 44 on the opposite inner faces of the outer 75

discs (Fig. 2). A transversely disposed yoke member 45 which may be of channel shape has an elongated central opening 46 (Fig. 5) through which loosely extends the governor shaft 21. The yoke member 45 may overlap and engage the thrust collar 40 (Fig. 2) so as to be axially slideable therewith on the governor shaft 21. A transverse disposed rock shaft 47 (Fig. 5) is rotatably mounted in the housing 15 and is positioned beneath the governor shaft 21 and in front of the yoke member 45. A sleeve 48 keyed or otherwise non-rotatably secured to the shaft 47 preferably has extending upwardly therefrom, spaced arms 49 that project through the elongated slot 46 so as to bear against the thrust collar 40 on opposite sides of the governor shaft 21 (Fig. 5). The rocker shaft 47 extends outwardly from one side of the housing 15 as at 50 (Fig. 5) and has clamped thereto a spring lever 51 as at 52 and has also connected thereto an actuating lever 53 which may be provided with spaced depending arms 54 that straddle the lever 51 and are keyed or otherwise clamped to the shaft 47 as at 55 (Fig. 7), so that actuation of either the lever 51 or 53 will cause rotation of the shaft 47. The upper end of the lever 53 may be provided with vertically spaced openings 56 for the purpose of adjustably connecting the lever 53 through suitable linkage to the throttle valve or the like of the engine or other control part thereof, so as to regulate the flow of the combustible mixture from the carburetor to the engine in accordance with the speed of rotation of the engine drive shaft and the governor shaft 21. The lever 51 is connected to one end of an auxiliary coil spring 57 as at 58 (Fig. 7). The opposite end of the light spring 57 is connected as at 59 to a lug or pin 60 extending outwardly from the side of the housing 15.

In order to resist the thrust resultant of the centrifugal forces at various speeds of the engine with which the governor is associated, means in the form of a spring assembly or system is operatively connected to the thrust collar or member 43 so as to exert a retractive force on the thrust collar and thus insure accurate control of the speed of the engine over a wide range of adjustments. This spring assembly includes an adjusting rock shaft 61 (Fig. 5) which is rotatably mounted in the spaced bearings 62 and 63 of the housing 15, and has an outwardly projecting portion 64 to which is clamped or otherwise non-rotatably secured the sleeve 65 of the speed adjusting lever 66 (Fig. 6). The lower end 67 of the lever 66 is arranged to engage a threaded screw 68 carried by a lug 69 on the outer side of the housing 15 and which is provided with a polygonal tool-receiving head 70 so as to control or regulate the rotative movement of the shaft 61 by the axial displacement of the adjusting screw 68. A locking nut 71 may be interposed between the lug 69 and the head 70 to maintain the screw 68 in a fixed adjusted position. Within the housing 15 the shaft 61 has mounted thereon a pair of spaced depending levers 72, each having a sleeve or hub portion 73 formed with an opening for receiving a set screw 74 to maintain the lever in a fixed position on the shaft 61 (Fig. 5). The lower end of each lever 72 is pivotally connected by a pin 75 to an intermediate portion of a segmental member or adjusting yoke 76 at points substantially in the horizontal plane of the governor shaft 21. As shown, the yokes 76 are semi-circular and each has a pair of inclined springs 77 and 78 connected at its ends as at 79. The

rear ends of the pair of springs 77 are connected as at 80 (Fig. 8) to a lug 81 on the end of the yoke member 45 and the pair of springs 78 are similarly connected as at 82 to a lug 83 on the opposite end of the yoke member 45. The two pairs of springs 77 and 78 are identical and are so suspended that the spring forces are balanced about the axis of the governor shaft 21. It will be noted that the outer or converging ends of the pairs of springs 77 and 78 are connected to the yoke member 45 which is movable axially on the governor shaft 21. The curved ends of the yoke members 76 to which the inner ends of the springs 77 and 78 are connected, are spaced from the governor shaft 21 and so positioned that the 10 springs 77 and 78 are located outside the zone of rotation and movement of the fly-weights 27. The yoke members 76 have a span of at least eight times the normal axial movement of the thrust collar 40 between positions corresponding to the 15 full-load and no-load positions of the governor throttle valve lever 53. It might be mentioned that the most favorable ratio of the span of the adjusting yokes 76 to the thrust collar 43 movement, is a function of the ratio of the initial and the final thrust forces at open-valve and no-load valve positions. In the form of governor disclosed, it has been found that a ratio of 8.3 to 1 has obtained desirable and efficient results though a change in the characteristics of the weights will alter this ratio.

As the adjusting yokes 76 are free to pivot on the pins 75 at a point relatively remote from a line through the points of support of the springs 77 and 78, slight inequalities in the length of the springs and slight departure of the adjusting lever pins 75 from the plane of the axis of the shaft 21 are compensated sufficiently to obviate unbalanced lateral pull on the thrust collar 40 and sleeve 33 which might be productive of undesirable friction and wear. The spaced arms 49 on the shaft 47 are yieldably held in engagement with the thrust collar 40 by the tension of the auxiliary spring 57 on the lever 51, and this force is little more than what is sufficient to balance 45 any reflex closing force on the lever 53 due to gas velocity forces on the throttle valve. Thus, the major portion of the force of the springs 77 and 78 is directly opposed to the force on the thrust collar 40 and sleeve 33 so that the thrust collar 50 normally is balanced about its axis with little resultant friction. When a low idling device is used, very little power is required to overcome the auxiliary spring 57 and close the throttle valve, with the result that no spring-loaded telescoping 55 throttle is required.

It will be seen that in normal operation, the shaft 21 is rotated at or above the speed of the engine shaft and the fly-weights 27 which are shiftable toward and away from the shaft 21 assume the position as shown in Figure 2. When the speed of the shaft 21 is increased, the centrifugal force causes the fly-weights to move outwardly which, in turn, actuates the arms 26 to move the sleeve 33 axially and rearwardly of the housing 15 and against the pressure of the auxiliary spring 57 which normally maintains the arms 49 in contact with the thrust collar 43. This axial displacement of the sleeve 33 also moves the yoke member 45 toward the rear of the housing 15 and at the same time extends the pair of springs 77 and 78 which are disposed at an acute angle to the governor shaft 21, so that the axes of these springs assume decreasing angles with respect to the axis of the shaft 21, 70 75

or the plane through the shaft axis and the median line of the spring yokes 76, as clearly shown in dotted lines in Figure 9. This acute angle is the inside angle as contrasted to the outside obtuse angle between a pair of springs such as 77 or 78. Thus, it will be seen that the pairs of springs 77 and 78 are movable in a direction substantially parallel with the axis of the shaft 21 and exert a retractive force on the yoke member 45 and the thrust collar 43 to oppose the centrifugal force developed by the radial movement or opening of the fly-weights 27. The auxiliary spring 57 normally holds the arms 49 on the shaft 47 yieldably against the thrust collar 43 with a force which is proportionally less with respect to the force exerted by the spring assembly, at the no-load position of the thrust collar 40, than the force exerted by the auxiliary spring 57 in relation to the force exerted by the pairs of springs 77 and 78 of the main assembly or system at the full-load position of the thrust collar 40. It is to be understood that the forces referred to are thus exerted at the highest speed for which the governor is designed to operate. It will be seen that the segmental yoke members 76 are pivotally connected to the levers 72 so that slight variations in the lengths and deflection rates of the springs 77 and 78, or slight departure of the pins 75 from the plane of the axis of the shaft 21 and the median line of the yoke 76 may be readily compensated.

The yieldable connection of the lever 51 by the auxiliary spring 57 to the housing 15 provides means for maintaining the rock shaft 47 and its associated parts at the most effective angle regardless at what position the throttle actuating lever may be in, to meet the requirements of various installations, and also to change the effect of the auxiliary spring 57. For instance, in the position shown in dotted lines in Figure 7, the spring 57 has the effect of a weaker spring, than in the normal position shown in solid lines. Thus, the moment of force is a decreasing one in the case of the dotted line position of the spring 57 and an increasing one in the normal position. It has been found that this novel arrangement may efficiently be used either to increase the sensitivity of the governor or to decrease it, as the best and most efficient operating conditions may require.

Thus, it will be seen that axial displacement of the yoke member 45 by outward swinging movement of the fly-weights expands or lengthens the pairs of springs 77 and 78 so as to cause the application of the resultant of the forces of these angularly supported springs to be exerted directly on the thrust collar 40 and the sleeve 33 in opposition to the centrifugal force developed by the outward movement of the fly-weights 27. The tension of the auxiliary spring 57 for normally urging the arms 49 into engagement with the thrust collar 40, remains constant throughout the range of speed adjustment and the force of the spring 57 is a relatively small part of the total spring force. It might be mentioned that this spring tension is usually a little more than is required to overbalance the air velocity forces which result in reducing the torque on the butterfly valve shaft of the engine or in the case of a valve shaft mounted in plain bearings, the sum of such forces and the frictional drag on the bearings due to the rather high loads resultant from the pressure differential on the upstream and downstream sides of the throttle valve when the latter is closed, is reduced to a minimum.

The housing 15 may be provided with the usual oil filling opening closed by the removable plug 13, also a drain plug 14 and the oil level plug 14' (Fig. 1).

In the form of the invention shown in Figure 8, the shaft 61 instead of being connected to an adjusting lever, such as the lever 66 (Fig. 6) previously described, is shown connected to a lever 88' in order that the governor may be efficiently used in association with a tractor. The 10 lever 88' is positioned convenient to the driver's seat and provides a wide range of adjustments when the spring assembly is used with a tractor.

In the modified form of the invention shown in Figures 11, 12 and 13, a single pair of angularly supported or inclined springs 84 are associated with the governor and substituted for the four springs previously described. Each of the springs 84 is connected at one end as at 85 to a spring adjusting link 86 (Figure 13) which, in turn, is pivotally connected as at 87 to a lever 88 fixed or keyed at its upper end as at 89 to the rock shaft 90. The front or forward ends of each of the springs 84 are connected as at 91 to the yoke member 92 that is axially slidable on the governor shaft 93 rotatably mounted in the housing 94. The axis of each of the springs 84 is disposed at an acute angle to the axis of the governor shaft and becomes more acute as the springs are lengthened. A sleeve 95 is axially slidable on the shaft 83 and has spaced flanges 96 and 97 between which is received the movable jaws 98 of the fly-weights 99 that are pivoted as at 100 to a yoke member 101 fixed to a sleeve 102 through which the governor shaft 93 extends so as to be operatively connected to the engine shaft in any suitable manner, not shown. The fly-weights 99 are formed with inwardly disposed arms 103 having pins 104 that engage the flange 96 so as to move the sleeve 95 axially to the left as shown in Figure 11, when the speed of the shaft 102 moves the jaws 98 outwardly to the position as shown in Figure 11. A rock shaft 105 similar to the shaft 47 previously described, is rotatably mounted in the housing 94 and carries the spaced arms 106 (Fig. 13) which bear against the yoke member 92 which, in turn, engage the thrust collar 107 which may be similar in operation to the thrust collar 43 previously described. The plane of the springs 84 and their associated parts, it will be noted from Figure 13 of the drawing, lie in the same horizontal plane as the governor shaft 93 and the springs are so positioned so as not to contact either the fly-weight jaws 98 when extended to assume a more acute angle and the position as shown in Figure 11 during the operation of the governor.

It will be noted that in all forms of the invention shown, the spring assembly or mounting is so constructed and associated with the governor shaft to increase the rate of the effective axial resultant of the spring forces when the yoke member on the governor shaft is displaced axially and the springs extended to assume decreasing angles with respect to the axis of the governor shaft for the purpose of increasing the governed speed.

The effective axial resultant force of the four springs as disclosed in Figure 2 will be four times the tension of the individual springs multiplied by the cosine of the angle between the axes of the springs and the plane of the axis of the governor shaft through the median line of the spring mountings.

The forces exerted on the thrust collar, of

course, can be readily computed by tests at suitable rotative speeds at the full-load and no-load positions of the thrust collar. The fly-weights must be so proportioned that the force for full-load position is more than 55% of the force at no-load position. Moreover, calculations may be made for the highest rotative speed of the governor shaft 21 required for control of the largest engine on which the governor may be used. The same governor unit with the same springs may be used for many installations using lower rotative speeds for smaller engines employing smaller throttle valves. In this way, a standard unit can be made with the advantages from a cost standpoint, of larger and more economical production of a single model.

Using fly-weights, such as shown, it has been found that a spring assembly or attachment in which the outside angle of each pair of springs approximates 94° for the highest speed adjustment at no-load position, gives satisfactory results at lower speeds when the characteristics of the auxiliary spring 57 are selected to overbalance the reactive force on the throttle actuating lever 53 due to gas velocity closing forces on the throttle valve. Variations in the auxiliary spring 57 are the only ones required for various installations and it is to be observed that several points of attachment of this spring to the throttle actuating lever are provided, to vary the effect of a single spring design in producing torque about the axis of the throttle actuating lever shaft 47. Consistent performance at varying speeds requires an auxiliary spring of low deflection rate, in order that its initial force may be high in proportion to the final force, at no-load position. It will be observed that the proportion of the spring force for open-valve position to the force at no-load position for low speed adjustment, is somewhat less than the proportion at those positions, for high-speed adjustment. This is necessary because the required rate of throttle valve opening with increasing loads is somewhat less at low engine speed than at high speed, though not sufficiently less to give satisfactory results when using a spring of uniform deflection rate at various adjustments. At cut-off at low speed adjustment the valve will start to close slightly early, but for 10 or 15 degrees of movement its throttling effect will be very slight. It will be seen that the auxiliary spring 57 coacts with the main spring assembly to provide a complete system of control. Moreover, by virtue of the adjustability of the auxiliary spring 57, it has been found to be of great value in special applications at fixed speeds.

In Figure 14, the ordinates represent the total thrust collar movement and the abscissae indicate the thrust in pounds, so that the forces are plotted against the travel of the thrust collar along the governor main shaft. The open valve position is represented at the left and the no-load valve position at the right. The spring force curves are lettered N, P, S, R, O, M and T, and are numbered 1 to 8, inclusive. These lines are dotted and solid and arranged in transverse pairs, the lower or dotted line of each pair representing the main spring system, the upper solid line the total force including the auxiliary spring force. It will be noted that the auxiliary spring force in the numbered curve lines are the same values showing the performance of variable speed units without change in the auxiliary spring tension or in the position of the spring

level. The spring thrust force is indicated on this chart. The transverse dotted and solid lines 1 and 5 indicate a maximum of 3000 R. P. M.; the transverse lines 2 and 6 a maximum of 2302 R. P. M.; transverse lines 3 and 7 a maximum of 1656 and transverse lines 4 and 8 a maximum of 1152 R. P. M.; the transverse lines NT and NM a maximum of 2687 R. P. M.

The lettered curves show the effect of changing the auxiliary spring arrangement for more accurate performance at a certain speed. The lines PO and NM represent the same adjustment of the auxiliary spring as in the other curves and the lines SR and NT show the effect of adding tension in the auxiliary spring and changing the position of the auxiliary spring lever. The effective deflection rates of both the main spring system and the auxiliary spring system, on a pounds per inch basis, are diminished, as is required to make the governor more accurate. It is apparent that when the auxiliary spring tension is increased, the main spring-system adjustment must be backed off to bring the no-load speed to its original value, and the effect is to make the main spring angles slightly more obtuse and, accordingly, to change the effective rate of the spring system in the desired direction.

The angles of the main spring axes to the shaft axis for the solid-line curves are substantially 47°, 54°, 62° and 72°, and the corresponding thrust-collar movements from the full-load position are .251, .265, .277 and .287 inches, respectively. From these figures and the lengths and deflection rates of the springs, the thrusts are readily computed. The forces plotted are for a single spring of the main spring system and, accordingly, to keep the correct proportion, one-fourth of the auxiliary spring tension is shown in each case. The engine performance chart shown in Figure 15 is correlated with the spring force chart, the points at the left side of the force dia- phragm showing the forces for wide open throttle, from which are computed the speeds at which the governor valve starts to close. It will be noted that at some speeds, with normal auxiliary setting, the governor valve can close slightly without affecting the power in the load range used in industrial engines.

The ordinates in this chart represent the R. P. M. of the engine, while the abscissae indicate the H. P. The oblique line A shows the horse-power of the engine at all speeds with open throttle, and the nearly vertical or upright lines B show the speeds at which the engine operates under reduced loads at various governor settings. With a 1.25 to 1 ratio of governor shaft to engine shaft speed, the 3000 R. P. M. speed of the governor shaft corresponds to 2400 R. P. M. engine speed. With some other ratio, such as 1.5 to 1, the range of adjustment 3 would be reduced, while the accuracy of the governor at the various speeds would be increased. The broken lines MN and TN correspond to the broken lines in the force diagram, and show a marked change in performance characteristic by a change in the auxiliary spring and lever setting. The dotted line 2-9 illustrates the performance to be expected of a governor with conventional spring designed for 2400 R. P. M., but adjusted down to 1740 R. P. M. no-load. It is apparent that such a governor would be of little value as a variable speed unit, even in the least exacting type of service.

It will be understood that the forms of the in-

vention shown are merely illustrative and that various modifications and changes may be made as come within the scope of the following claims.

I claim:

5. In a centrifugal governor, a housing, a governor shaft rotatably mounted in the housing, centrifugal means connected to said shaft so as to be operable by the speeds thereof, a spring assembly for resisting the thrust resultants of the centrifugal operation of the governor at various speeds, said spring assembly including a supporting shaft mounted in the housing, at least one pair of springs disposed on opposite sides and at an angle relative to the governor shaft, said springs having inner and outer ends, a yoke member axially slideable on the governor shaft, the inner ends of said springs being connected to said yoke member, means pivotally connecting the outer ends of the springs to said supporting shaft, and yieldable means for normally urging the thrust member axially toward the centrifugal means.
20. In a centrifugal governor, a housing, a governor shaft rotatably mounted in the housing, centrifugal means connected to said shaft so as to be operable by the speeds thereof, a spring assembly for resisting the thrust resultants of the centrifugal operation of the governor at various speeds, said spring assembly including a rock shaft mounted in said housing and at an angle relative to the governor shaft, at least one pair of springs disposed on opposite sides and at an acute angle relative to the governor shaft, a yoke member axially slideable on the governor shaft, the converging ends of the springs being connected to said yoke member, means pivotally connecting the diverging ends of the springs to said rock shaft, an axially displaceable thrust member on the governor shaft between the centrifugal means and said yoke member, and yieldable means for normally urging the thrust member axially toward the centrifugal means.
25. In a centrifugal governor, a housing, a governor shaft rotatably mounted in the housing, centrifugal means connected to said shaft so as to be operable by the speeds thereof, a spring assembly for resisting the thrust resultants of the centrifugal operation of the governor at various speeds, said spring assembly including a rock shaft mounted in said housing and at an angle relative to the governor shaft, at least one pair of springs disposed on opposite sides and at an acute angle relative to the governor shaft, a yoke member axially slideable on the governor shaft, the converging ends of the springs being connected to said yoke member, means pivotally connecting the diverging ends of the springs to said rock shaft, an axially displaceable thrust member on the governor shaft between the centrifugal means and said yoke member, and yieldable means for normally urging the thrust member axially toward the centrifugal means.
30. In a centrifugal governor, a housing, a governor shaft rotatably mounted in the housing, centrifugal means connected to said shaft so as to be operable by the speeds thereof, a spring assembly for resisting the thrust resultants of the centrifugal operation of the governor at various speeds, said spring assembly including a rock shaft mounted in said housing and at an angle relative to the governor shaft, at least one pair of springs disposed on opposite sides and at an acute angle relative to the governor shaft, a yoke member axially slideable on the governor shaft, the converging ends of the springs being connected to said yoke member, means pivotally connecting the diverging ends of the springs to said rock shaft, an axially displaceable thrust member on the governor shaft between the centrifugal means and said yoke member, and yieldable means for normally urging the thrust member axially toward the centrifugal means.
35. In a centrifugal governor, a housing, a governor shaft rotatably mounted in the housing, centrifugal means connected to said shaft so as to be operable by the speeds thereof, a spring assembly for resisting the thrust resultants of the centrifugal operation of the governor at various speeds, said spring assembly including a rock shaft mounted in said housing and at an angle relative to the governor shaft, at least one pair of springs disposed on opposite sides and at an acute angle relative to the governor shaft, a yoke member axially slideable on the governor shaft, the converging ends of the springs being connected to said yoke member, means pivotally connecting the diverging ends of the springs to said rock shaft, an axially displaceable thrust member on the governor shaft between the centrifugal means and said yoke member, and yieldable means for normally urging the thrust member axially toward the centrifugal means.
40. In a centrifugal governor, a housing, a governor shaft rotatably mounted in the housing, centrifugal means connected to said shaft so as to be operable by the speeds thereof, a spring assembly for resisting the thrust resultants of the centrifugal operation of the governor at various speeds, said spring assembly including a rock shaft mounted in said housing and at an angle relative to the governor shaft, at least one pair of springs disposed on opposite sides and at an acute angle relative to the governor shaft, a yoke member axially slideable on the governor shaft, the converging ends of the springs being connected to said yoke member, means pivotally connecting the diverging ends of the springs to said rock shaft, an axially displaceable thrust member on the governor shaft between the centrifugal means and said yoke member, and yieldable means for normally urging the thrust member axially toward the centrifugal means.
45. In a centrifugal governor, a housing, a governor shaft rotatably mounted in the housing, centrifugal means connected to said shaft so as to be operable by the speeds thereof, a spring assembly for resisting the thrust resultants of the centrifugal operation of the governor at various speeds, said spring assembly including a rock shaft mounted in said housing and at an angle relative to the governor shaft, at least one pair of springs disposed on opposite sides and at an acute angle relative to the governor shaft, a yoke member axially slideable on the governor shaft, the converging ends of the springs being connected to said yoke member, means pivotally connecting the diverging ends of the springs to said rock shaft, an axially displaceable thrust member on the governor shaft between the centrifugal means and said yoke member, and yieldable means for normally urging the thrust member axially toward the centrifugal means.
50. In a centrifugal governor, a housing, a governor shaft rotatably mounted in the housing, centrifugal means connected to said shaft so as to be operable by the speeds thereof, a spring assembly for resisting the thrust resultants of the centrifugal operation of the governor at various speeds, said spring assembly including a rock shaft mounted in said housing and at an angle relative to the governor shaft, at least one pair of springs disposed on opposite sides and at an acute angle relative to the governor shaft, a yoke member axially slideable on the governor shaft, the converging ends of the springs being connected to said yoke member, means pivotally connecting the diverging ends of the springs to said rock shaft, an axially displaceable thrust member on the governor shaft between the centrifugal means and said yoke member, and yieldable means for normally urging the thrust member axially toward the centrifugal means.
55. In a centrifugal governor, a housing, a governor shaft rotatably mounted in the housing, centrifugal means connected to said shaft so as to be operable by the speeds thereof, a spring assembly for resisting the thrust resultants of the centrifugal operation of the governor at various speeds, said spring assembly including a rock shaft mounted in said housing and at an angle relative to the governor shaft, at least one pair of springs disposed on opposite sides and at an acute angle relative to the governor shaft, a yoke member axially slideable on the governor shaft, the converging ends of the springs being connected to said yoke member, means pivotally connecting the diverging ends of the springs to said rock shaft, an axially displaceable thrust member on the governor shaft between the centrifugal means and said yoke member, and yieldable means for normally urging the thrust member axially toward the centrifugal means.
60. In a centrifugal governor, a housing, a governor shaft rotatably mounted in the housing, centrifugal means connected to said shaft so as to be operable by the speeds thereof, a spring assembly for resisting the thrust resultants of the centrifugal operation of the governor at various speeds, said spring assembly including a rock shaft mounted in said housing and at an angle relative to the governor shaft, at least one pair of springs disposed on opposite sides and at an acute angle relative to the governor shaft, a yoke member axially slideable on the governor shaft, the converging ends of the springs being connected to said yoke member, means pivotally connecting the diverging ends of the springs to said rock shaft, an axially displaceable thrust member on the governor shaft between the centrifugal means and said yoke member, and yieldable means for normally urging the thrust member axially toward the centrifugal means.
65. In a centrifugal governor, a housing, a governor shaft rotatably mounted in the housing, centrifugal means connected to said shaft so as to be operable by the speeds thereof, a spring assembly for resisting the thrust resultants of the centrifugal operation of the governor at various speeds, said spring assembly including a rock shaft, spaced pairs of co-acting springs dis-

posed on opposite sides and at an acute angle relative to the governor shaft, a yoke member axially slidable on the governor shaft, the converging ends of the springs being connected to said yoke member, means pivotally connecting the diverging end of the springs to said rock shaft, an axially displaceable thrust member on the governor shaft, and yieldable means for normally urging the thrust member axially toward the centrifugal means.

5. In a centrifugal governor, a housing, a governor shaft rotatably mounted in the housing, centrifugal means connected to said shaft so as to be operable by the speeds thereof, a spring assembly for resisting the thrust resultants of the centrifugal operation of the governor at various speeds, said spring assembly including a rock shaft, a pair of inclined springs disposed at an acute angle relative to the governor shaft and positioned on opposite sides thereof, a yoke member axially slidable on the governor shaft, the converging ends of the springs being connected to said yoke member, link means pivotally connecting the diverging ends of the springs to said rock shaft, an axially displaceable thrust member on the governor shaft, and yieldable means for normally urging the thrust member axially toward the centrifugal means.

6. In a centrifugal governor, a rotary governor shaft, fly-weights pivotally mounted on said shaft so as to be movable radially thereto, a sleeve axially slidable on said shaft and having spaced annular flanges, said fly-weights normally being positioned between said flanges, means operatively connecting the fly-weights to one of said flanges so that radial outward movement of the fly-weights displaces axially the sleeve, a thrust member on said shaft and engaging the other of said flanges, a spring assembly for resisting the thrust resultants of the centrifugal operation of the governor at various speeds, said spring assembly including at least one pair of springs disposed on opposite sides of the governor shaft, a yoke member connected to said springs and axially slidable on the governor shaft so as to engage and be movable with said thrust member, a rock shaft mounted in said housing and having an arm engaging said thrust member, an auxiliary spring connected at one end to said housing, and means operatively connecting the opposite end of said auxiliary spring to said rock shaft for normally opposing the force of the fly-weights and arranged to be overcome thereby when the speed of the governor shaft moves the fly-weights outwardly relative to the governor shaft.

7. In a centrifugal governor, a rotary governor shaft, fly-weights pivotally mounted on said shaft so as to be movable radially thereto, a sleeve axially slidable on said shaft and having spaced annular flanges, said fly-weights normally being positioned between said flanges, means operatively connecting the fly-weights to one of said flanges so that radial outward movement of the fly-weights displaces axially the sleeve, a thrust member on said shaft and engaging the other of said flanges, a spring assembly for resisting the thrust resultants of the centrifugal operation of the governor at various speeds, said spring assembly including two pairs of springs, each pair of springs having converging outer ends, a yoke member axially slidable on said governor shaft, means connecting the outer ends of said pairs of springs to said yoke member, a rock shaft disposed transversely relative to said

governor shaft, a pair of spaced depending levers fixed to said rock shaft so as to be movable therewith, spaced segmental members pivotally connected intermediate their ends to said levers, the inner ends of said pairs of springs being connected to said segmental members, an actuating shaft rotatably mounted in said housing and having an arm engaging said thrust member, yieldable means connected to said actuating shaft for normally urging said arm against the thrust collar, and said pairs of springs being disposed at an angle to the axis of the governor shaft and displaceable to assume decreasing angles with respect to the governor shaft axis upon axial displacement of the yoke member by the radial movement of the fly-weights upon increase in speed of the governor shaft.

8. A spring assembly for variable speed centrifugal governors having a governor shaft, said assembly including an actuating rock shaft having spaced arms pivotally connected thereto and disposed transversely of the governor shaft, a yoke member axially slidable on the governor shaft, and inclined springs connected to said arms and said yoke member, said springs being disposed on opposite sides of the governor shaft and arranged to assume decreasing angles with respect to the governor shaft axis upon axial displacement of the yoke member.

9. A spring assembly for variable speed centrifugal governors including an actuating rock shaft, a pair of spaced depending levers keyed to said rock shaft, a segmental member pivotally connected intermediate its end to each of said levers, a transversely disposed yoke member axially slidable on the governor shaft, spaced pairs of inclined springs connected at their forward ends to said yoke member, one pair of the springs being connected at their rear ends to the ends of a segmental member, the other pair of springs being connected to the ends of the other segmental member, and said pairs of springs being disposed on opposite sides of the governor shaft and arranged to assume decreasing angles with respect to the governor shaft axis upon axial displacement of the yoke member.

10. A governor of the class described including a housing, a governor shaft rotatably mounted in the housing, fly-weights pivotally connected to said governor shaft and movable radially and outwardly thereof when the shaft reaches a predetermined speed, a thrust collar axially slidable on said governor shaft and arranged normally to engage the fly-weights for opposing the centrifugal action thereof, a yoke member slidably on said governor shaft and engaging said thrust collar so as to be displaceable therewith, an actuating shaft rotatably mounted in the housing and extending transversely of the governor shaft, said actuating shaft having an arm engaging said thrust collar for normally opposing the centrifugal action of the fly-weights, an operating lever connected to said actuating shaft, yieldable means connected to the housing and said actuating shaft for urging said arm against said thrust collar, a spring assembly including a rock shaft mounted in said housing for controlling the speed of the governor shaft, at least one pair of springs disposed on opposite sides and at an acute angle relative to the governor shaft, said springs having inner and outer ends, the inner ends of said springs being connected to said yoke member, means pivotally connecting the outer ends of the springs to said rock shaft,

and means for angular adjustment of the rock-shaft.

11. A governor of the class described, including a housing, a governor shaft rotatably mounted in the housing, fly-weights pivotally connected to said governor shaft and movable radially and outwardly thereof when the shaft reaches a predetermined speed, a thrust collar axially slidable on said governor shaft and arranged normally to engage the fly-weights for opposing the centrifugal action thereof, a yoke member slidable on said governor shaft and engaging said thrust collar so as to be displaceable therewith, an actuating shaft rotatably mounted in the housing and extending transversely of the governor shaft, said actuating shaft having an arm engaging said thrust collar for normally opposing the centrifugal action of the fly-weights, an operating lever

10

15

and an angularly adjustable spring lever connected to said actuating shaft, yieldable means connected to the housing and said spring lever for urging said arm against said thrust collar, a spring assembly including a rock shaft mounted in said housing for controlling the speed of the governor shaft, means operatively connecting said assembly to said yoke member, and means for angular adjustment of the rock-shaft.
